UNITED STATES PATENT OFFICE.

JAMES N. BALLOU AND JOSEPH J. SHIRLEY, OF BUFFALO, NEW YORK.

STEEL GRAIN-BIN.

SPECIFICATION forming part of Letters Patent No. 699,439, dated May 6, 1902.

Application filed May 4, 1901. Serial No. 58,725. (No model.)

To all whom it may concern:

Be it known that we, JAMES N. BALLOU and JOSEPH J. SHIRLEY, citizens of the United States, residing at Buffalo, in the county of Erie and State of New York, have invented certain new and useful Improvements in Steel Bins for Grain-Elevators; and we do hereby declare the following to be a full, clear, and exact description of the invention, such as will enable others skilled in the art to which it appertains to make and use the same, reference being had to the accompanying drawings, and to figures of reference marked thereon, which form a part of this specification.

Our invention relates to improvements in steel bins for grain-elevators and storage-houses, and more particularly to that form commonly known as the "cylinder" construction, which consists of separate and complete steel cylinders placed closely together in rows, the contacting sides being bolted or riveted together.

The object of our invention is to produce a series of bins possessing sufficient structural strength for the purpose and involving a considerable saving in the amount of material required.

To that end our invention consists of a series of bins each composed of separate corner-sheets and interposed flat side sheets, the flat side sheets being secured between the contiguous corner-sheets of separate adjacent bins to form an inner side wall common to any two adjacent bins.

We will now minutely describe the manner in which we have carried out our invention and then claim what we believe to be novel.

In the drawings, Figure 1 is a top plan view showing a series of nine of our improved bins. Fig. 2 is a partial elevation of Fig. 1, and Fig. 3 is a modification.

Referring to the drawings, 11 are the bins, with central outlets 2 in their floors, through which the stored grain is removed. Each bin is composed of four corner-sheets 3, preferably curved, as shown in Fig. 1, and interposed between these curved corner-sheets 3 are the

side sheets 4, preferably straight or flat, as shown in Fig. 1. Where the side sheets 4 are on the outside, they are secured between adjacent corner-sheets of the same bin; but where they are located within they are secured between the contiguous corner-sheets of separate adjacent bins, thus serving in the double capacity of one side wall for two adjacent bins.

Between any four adjacent bins constructed as above described are the inside pocket-bins 5, which may have separate outlets in their floors or they may be tapped into the main bins. The outside pocket-bins 6 are formed by the sheets 7, which are secured to the side sheets 4 and corner-sheets 3, as shown in Fig. 1.

The different parts of our improved bins 65 are all bolted or riveted together so as to break joints, as clearly shown in Fig. 2.

In Fig. 3 we have shown a modification of the corner-sheet 3, which instead of being curved is shown straight at the central portion 8, with bent end flanges 9 9, which are secured to the side sheets in building up the bins.

Under our improved construction each inner side sheet 4 serves in the double capacity 75 of a side wall for two adjacent bins, and in this manner a very considerable saving in material is effected over the common system of providing separate and complete cylinders secured together at their contacting sides. 80 At the same time our improved bins possess sufficient structural rigidity to meet the strains imposed upon them by the stored grain.

We claim—

1. A series of bins for grain-elevators and storage-houses, each bin composed of separate corner-sheets and interposed flat side sheets, the flat side sheets being secured between the contiguous corner-sheets of separate adjacent bins to form an inner side wall common to any two adjacent bins.
2. A series of bins for grain-elevators and storage-houses, each bin composed of sepa-

rate corner-sheets and interposed flat side sheets, the flat side sheets being secured between adjacent corner-sheets of the same bin to form outer side walls, and secured between 5 the contiguous corner-sheets of separate adjacent bins to form an inner side wall common to any two adjacent bins.

In testimony whereof we have signed our

names to this specification in the presence of two subscribing witnesses.

JAMES N. BALLOU.
JOSEPH J. SHIRLEY.
